UNITED STATES PATENT OFFICE.

ELMER E. LANE, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING-MACHINE.

1,260,552.

Specification of Letters Patent. Patented Mar. 26, 1918.

Application filed July 19, 1915. Serial No. 40,679.

To all whom it may concern:

Be it known that I, ELMER E. LANE, a citizen of the United States, residing at Beverly, in the county of Essex and State 5 of Massachusetts, have invented certain new and useful Improvements in Skiving Machines; and I do hereby declare the following to be a full, clear, and exact description of the invention, such as will enable others 10 skilled in the art to which it appertains to make and use the same.

This invention relates to skiving machines and more particularly to a method of and apparatus for skiving blanks stiffened with 15 a filler which becomes sticky when heated.

In the manufacture of boots and shoes certain of their parts, such as the toe and heel, are supported by stiffeners, a box toe being used at the toe and a counter at the 20 heel. The box toe and counter are placed inside the upper and united with the sole to hold them firmly in place. These stiffeners are skived off to a feather edge on their border so that they may be secured in 25 place without any bumps or laps to give a smooth, finished appearance to the shoe. The stiffeners are often made of a porous fabric material filled with shellac or similar composition which makes the fabric hard 30 and stiff at ordinary temperatures. This fabric may be softened by solvents or heat to allow it to be molded into shape and, after being molded, is allowed to harden in its finished form. The stiffener blanks are 35 skived while the fabric is stiff and hard, and the treatment of the blank in the skiving machine forms considerable dust and waste. The skiving operation creates sufficient heat to make the dust and waste sticky, 40 so that it adheres to the skiving roll and knife. Any waste that might stick in the cavity or matrix of the skiving roll will modify the character of the skiving of the blank and, in many cases, require the skived 45 blank to be discarded and the machine stopped to clean the parts.

The primary object of the present invention is to provide a skiving machine in which blanks containing a filler that becomes sticky when heated may be successfully skived without the interference of waste material formed in the skiving operation.

In accordance with this object, one fea-

ture of the invention contemplates the provision in a skiving machine of means to moisten the surface of a roll to cool it, and assist in keeping it clear of waste material formed in the skiving operation. The use of an excess of water in cooling the skiving parts tends to wash the dust formed from the skiving operation into the bearings of the die or matrix roll. To avoid the use of an excess of water, the preferred embodiment of this feature of the invention contemplates applying moisture only to the die roll. To employ a minimum amount of water required to cool the parts, the best form of the invention that has been devised consists of a device to direct a spray of 70 water only into the cavity or matrix of the die roll.

Another feature of the invention contemplates a method of skiving blanks which have a stiffening filler that becomes sticky 75 when heated comprising, supporting the blanks for a predetermined type of cut, skiving the blanks when so supported, and cooling the operating parts to prevent the waste of the skiving operation from adhering to the parts. The stiffened blanks are not affected by and do not absorb water, so that the application of a film of water directly on the blank to be carried to the parts or placed on the machine between the blank 80 and the matrix of the die roll, or between the blank and the skiving knife, will act to keep the machine parts cool. When the parts are cool, the waste does not become sticky and the water acts as a lubricant to 90 keep the parts clear of waste.

A further feature of the invention contemplates the provision in a skiving machine of means for moistening a roll and means for controlling the amount of moisture delivered to the roll. By delivering only a sufficient quantity of water to moisten the cavity of the die roll, the dust of the skiving operation is not washed into the bearings of the skiving rolls, and an economical use of water is insured. In the preferred form of this feature of the invention, the means for controlling the quantity of liquid delivered to the die roll also controls the time in which the liquid is delivered to 100 the die roll. Since the cavity of the die roll is that portion which is most liable to be clogged with waste, the liquid controlling

means is timed so as to deliver liquid only to the cavity of the roll.

Other features of the invention relate to certain devices, combinations and arrangements of parts hereinafter described and claimed, the advantages of which will be apparent to those skilled in the art.

The features of the invention will be clearly understood from an inspection of the accompanying drawings, in which Figure 1 is a view in side elevation of a skiving machine embodying the preferred form of the invention; Fig. 2 is a longitudinal sectional view of the upper portion of the machine; Fig. 3 is a view in front elevation showing the moistening device assembled and its attachment to the machine frame, and Fig. 4 is a detail view partly in section, showing the construction of the liquid regulator.

The machine illustrated in the drawings has substantially the same construction, arrangement and mode of operation as the machine illustrated in the patent to Scott No. 969,987, patented September 13, 1910. This machine is provided with a positively driven die roll 10 and pressure roll 12 between which extends the cutting edge of a skiving knife 14, so that the skiving cut will be made at approximately the line of contact of the die and pressure rolls with a blank. The blanks are supported in a hopper 16 and held in a flat position by a follower 18. A reciprocating feed slide 20 having a pushing blade 22 feeds the blanks one at a time to the skiving rolls. In the skiving operation, the blanks pass between the pressure and die rolls and the pressure roll forces the blanks down into a matrix or cavity of the die roll, which has the shape of the article to be produced, and as a blank is carried along by the rolls, the skiving knife acts to trim off the excess material while the blank is supported in the cavity. The parts above referred to are the same as the parts shown and described in said patent, to which reference is hereby made for a detailed description of their construction and operation.

The blanks from which the shoe stiffeners are made, may consist of a fibrous or felty material which is saturated with a filling composition to give it a hard, stiff structure. The filling composition consists of shellac modified with various ingredients to lower its melting point, and the composition thoroughly permeates the blank. When the stiff blank is forced into the cavity of the die roll by the pressure roll, the pressure tends to crack it, and forms considerable dust. A further amount of dust and waste scraps is formed by the action of the skiving knife. The friction of feeding, pressing the blank into the die roll cavity, and cutting the skiving creates sufficient heat to melt

the fine dust particles, so that they stick to the parts with which they come in contact. To prevent the dust and waste material evolved in the skiving operation from becoming sticky, the skiving parts are cooled below the temperature of the melting point of the filling dust, so that the material does not adhere to the operating parts and interfere with the operation of the machine. For cooling the skiving mechanism, a spray of water is directed against the bottom of the cavity roll by a nozzle 24, which is connected by means of tubes 26 and 28 with a pressure pump 30 for supplying liquid under pressure. The nozzle 24 is the ordinary type of spraying nozzle which is constructed to break up the moistening liquid into fine particles and direct a stream of a predetermined cross-section against the die roll. A drip tank 32 is mounted on the machine frame below the die roll 10 in a position to catch any excess liquid which may fall from the die roll, and the drip tank is connected by a tube 34 with a reservoir 36 mounted at the side of the machine frame. Any liquid caught in the drip tank 32 is filtered by a fibrous material 38, conducted through the tube 34 into the reservoir 36, and from the reservoir it passes to the pump 30 by a connecting tube 40. The reservoir 36 and pump 30 are supported upon a bracket 42 attached to the side of the machine frame below the main driving shaft. The pump 30 is the ordinary type of rotary pump, and is provided with a pulley 43 which is connected to a pulley 44 on the main driving shaft by a belt 46; see Fig. 3.

Since the cavity of the die roll is the portion that is most liable to become gummed with dust and waste and thereby interfere with the skiving operation, the moistening liquid is intermittently sprayed into the die roll cavity. The moistening liquid has a washing or lubricating action as well as a cooling action which aids in keeping the cavity clear of waste. The quantity of liquid required to moisten the cavity of the die roll is sufficient to keep the skiving parts cool enough so that the dust will not stick to them. This application of moistening liquid is important because the die roll is kept clear of waste, the moisture from the cavity is carried by the blank to the other skiving parts, and the liquid is not spread over the entire roll to wash dust into the bearings. To insure that the water may be placed only in the cavity of the die roll, the water is admitted to the nozzle intermittently and at the time the cavity is directly opposite the nozzle. The admission of moistening liquid to the nozzle is controlled by a regulator 48 (Figs. 2, 3 and 4), which is connected between tubes 26 and 28 and acts as an automatic valve in opening and closing the liquid supply. The regulator

48 consists of a casing 50 with a cover 52 in which is rotatably mounted a valve plate 54. In assembling the regulator, a suitable packing is placed between the valve plate 54 and the casing, and the cover 52 is secured in place by means of screws 56. The regulator is mounted on a shaft 58 which passes through the casing and valve plate and is journaled in a bracket 60 attached to the 10 machine frame below the drip tank 32. The valve plate 54 is keyed to the shaft 58 and is rotatable therewith, but the casing is attached to the bracket by means of a screw 62 (Fig. 3) placed in the bracket and cover 15 plate 52. The valve plate 54 is rotated by a ratchet and pawl mechanism which is actuated by a connection with the feed slide of the skiving machine, and each reciprocation of the feed slide opens and closes the 20 supply of liquid to the nozzle 24. The ratchet 64 is locked on the shaft 58, and beside it is loosely mounted a pawl lever 66 which carries a pawl 68 that engages with the ratchet 64. The connections between the pawl lever 25 66 and the feed slide 20 comprise a link 86 connecting the free end of the pawl lever with the upper end of an arm 84, a rock shaft 72 to which the arm 84 is secured, and an arm 70 also secured to the rock shaft 72 30 and provided at its upper end with a slot 74 to receive the feed slide pin 76. The connection between the lever 84 and link 86 is made adjustable to provide for timing the movement of the valve plate 54 in admitting liquid at the proper time to the cavity 35 of the die roll.

The valve plate 54 of the regulator (Figs. 2 and 4), has a series of openings 90 that are adapted to register with the open ends 40 of the tubes 26 and 28 at their connection with the casing 50 and cover 52 respectively. The period of time in which an opening 90 of the plate 54 will remain in register with the tubes 26 and 28 to permit the moistening liquid to flow to the cavity roll, depends upon the action of the ratchet and its actuating mechanism. This may further be modified by changing the size of the openings 90 to admit a greater 50 or smaller quantity of water, or by making the openings elongated so that they will admit water to the tubes 26 and 28 through a greater arc of movement of the plate 54. The connection of the regulator plate 55 with the feeding mechanism may be accurately adjusted to admit moisture only when the cavity is directly opposite the nozzle, and the amount of water may be regulated to admit only a sufficient quantity to completely moisten the cavity. After a blank 60 has passed between the rolls and has been skived, the cavity of the die roll is left comparatively dry and will be moistened again when it is opposite the nozzle 24. The film 65 of liquid which is placed between the blank

and the cavity of the die roll is sufficient to keep the temperature of the cavity roll low enough to prevent the skivings and dust formed from becoming sticky, and thus obviate the interference of this material with the skiving operation.

Having described the preferred form of the invention, what is claimed as new is:

1. A skiving machine having, in combination, a skiving knife, a pressure roll, a die roll, and means for moistening the surface of one of the rolls to prevent the work from adhering to the roll.

2. A skiving machine having, in combination, a skiving knife, a pressure roll, a die roll, and means for moistening the surface of the die roll.

3. A skiving machine having, in combination, a skiving knife, a pressure roll, a die roll, and means for intermittently moistening the die roll.

4. A skiving machine having, in combination, a skiving knife, a pressure roll, a die roll, and means for moistening less than the entire surface of the die roll.

5. A skiving machine having, in combination, a skiving knife, a pressure roll, a die roll, and means for directing a spray of liquid into the cavity only of the die roll.

6. A skiving machine having, in combination, a skiving knife, a pressure roll, a die roll, means for moistening a roll, and means for controlling the amount of liquid supplied to the roll.

7. A skiving machine having, in combination, a skiving knife, a pressure roll, a die roll, means for directing a spray of liquid on to the die roll, a source of liquid supply, and a regulator for controlling the admission of liquid to the spraying means.

8. A skiving machine having, in combination, a skiving knife, a pressure roll, a die roll, means for directing liquid to the die roll, means for supplying liquid under pressure to the directing means, and a regulator between the supply and directing means for intermittently cutting off the supply of liquid to the liquid directing means.

9. A skiving machine having, in combination, a skiving knife, a pressure roll, a die roll, means for feeding blanks to the rolls, a nozzle for spraying the die roll, a pressure pump, a tube connecting the pump with the nozzle, and a regulator in the tube operated by the feeding means for controlling the supply of liquid to the nozzle.

10. A skiving machine having, in combination, a skiving knife, a die roll, a nozzle below the die roll, a tube connecting the nozzle with the source of liquid supply, means for actuating the rolls, and means for admitting liquid to the nozzle only when the die cavity is opposite the nozzle.

11. A skiving machine having, in combination, a skiving knife, a pressure roll, a

die roll, a nozzle below the die roll, a tube connecting the nozzle with the source of liquid supply, a regulator mounted in the tube, feeding mechanism for supplying blanks to the feed rolls, operative connections between the feeding mechanism and the regulator, and means for actuating the rolls and feeding mechanism.

12. A skiving machine having, in combination, a skiving knife, pressure and die rolls, a nozzle for spraying the die roll having a tube connection with a pressure pump, a reservoir connected with the pressure pump, a drip tank under the die roll, and a return connection between the drip tank and reservoir.

13. The method of skiving blanks having a stiffening filler which becomes sticky when heated comprising, supporting the blanks for a predetermined type of cut, skiving the blanks when so supported, and cooling the operating parts to prevent the waste of the skiving operation from adhering to the parts.

14. The method of skiving blanks having

a stiffening filler which becomes sticky when heated comprising, supporting the blanks for a predetermined type of cut, skiving the blanks when so supported, and applying a coating of water between the blanks and an operating part to prevent the skivings from adhering to the parts.

15. The method of skiving blanks having a stiffening filler which becomes sticky when heated comprising, supporting the blanks for a predetermined type of skiving, moving the supported blanks across a cutter, and cooling the supporting means to prevent the skived portion of the blanks from adhering thereto.

16. The method of skiving blanks having a stiffening filler which becomes sticky when worked in a machine comprising, feeding a blank to a skiving mechanism provided with a matrix, forcing the blank into the matrix of the skiving mechanism, applying a film of moisture between the blank and the matrix, and skiving the blank near the line of contact of the matrix with the blank.

ELMER E. LANE.
